UNITED STATES PATENT OFFICE.

MADISON DAGGER, OF NEWTOWN, INDIANA.

FENCE.

SPECIFICATION forming part of Letters Patent No. 275,891, dated April 17, 1883.

Application filed December 29, 1882. (No model.)

To all whom it may concern:

Be it known that I, MADISON DAGGER, of 5
Newtown, in the county of Fountain and State
of Indiana, have invented certain new and use-
ful Improvements in Fences, of which the fol-
lowing is a full, clear, and exact description.

This invention consists in a worm rail and
wire fence in which double posts and cross-
stakes are used, whereby a very superior fence
10 at little cost is produced, the double posts sup-
porting the fence and holding the wires at any
desired height above the top rail, and the
stakes being held firmly against the rails,
pressed together, and locked with wires, and
15 the whole firmly banded together, there being
bands around the stakes and top rails that se-
curely hold them from being displaced by stock
of any kind. By this construction of fence
less "worm" is needed, and a greater length
20 of fence can be made with the same amount of
rails, inasmuch as the mode of fastening se-
curely holds the fence against wind or other
forces, and the fence can be "stretched," as it
is termed, to greater extent than usual, and
25 this reduces the amount of rails required.

Reference is to be had to the accompanying
drawing, forming a part of this specification,
which represents a view in perspective of a
fence in part embodying my invention.

30 A A are the rails of a worm-fence, and B B
double posts arranged on opposite sides of the
rails. There may be any number of these
double posts, at suitable distances apart, in
the length of the fence; but only a few of such
35 will be required, inasmuch as the rails are sup-
ported intermediately of them by inclined
stakes C C, arranged to press firmly against
the top rail in the panels, and to bear against
and cross one another at any desired height
40 above the top rails and intermediately be-
tween upper and lower longitudinal wires, D
D. These longitudinal wires may be arranged
so that the lowest of them will average one
foot (more or less) above the top rails, and are
45 stretched from one set of double posts B B to
another throughout the series of them, pass-
ing, respectively, between the stakes C C in
each pair of them, and so that each wire
passes, respectively, on opposite sides of said
50 stakes to one another above and below the
crutch or crossing junction of the stakes.
These wires serve to give height to the fence,

and also to hold it steady. This locking of
the stakes with the longitudinal wires is im- 55
portant, as also is the use of double posts in-
stead of single ones, to hold the rails which
pass in between them. Both stakes and posts
are firmly driven into the ground, and the two
stakes of each pair of stakes C C are not only 60
firmly united to one another, where they cross,
by a wire band, E, but said band is also
passed above and below the longitudinal wires
D D to bind the whole firmly together, and
said stakes are further bound or lashed to the 65
top rail in each panel by a wire band, F, which
holds the top rail from being displaced by
stock of any kind.

A fence constructed as described is both
light, cheap, and secure alike against hogs as
other animals, and it is relieved from all top- 70
heaviness and extended exposure to the wind.
An old worn-out ordinary worm-fence will fur-
nish rails and stakes enough to construct my
improved fence, and with but a small cost for
wire, and a greater length of fence can be 75
made with the same rails, as the mode of hold-
ing the fence makes it secure from wind and
other disturbing forces. It will be found much
lighter, stronger, and cheaper than other worm
and stake fences, either employing single or 80
double wooden riders or longitudinal wires
differently arranged relatively to the stakes
and rails and not using double posts.

Having thus fully described my invention, I
claim as new and desire to secure by Letters 85
Patent—

In a combined worm, stake, and wire fence,
the combination of the double posts B B, the
rails A A, arranged to pass in between said 90
posts, the crossing stakes C C, arranged to
bear or press against and support the top rails,
the longitudinal wires D D, stretched to con-
nect the several double posts above the top
rails, and arranged to pass above and below
the crossing junctions of the stakes, on oppo- 95
site sides of them, as described, and the bands
E F, applied to bind the stakes to the top rails
and the stakes and longitudinal wires together,
essentially as and for the purposes herein set
forth.

MADISON DAGGER.
